IMPACT TOOL

Charlie D. Williams, Pasadena, Calif.

Application May 22, 1948, Serial No. 28,642

1 Claim. (Cl. 1-47)

1

This invention relates to a nail driving device. More particularly the invention relates to a device for driving nails and tacks in comparatively inaccessible places and to replace a conventional hammer in such application. Devices of this character are commonly referred to as tube hammers.

The tube hammer of the invention comprises broadly an adjustable, elongated sleeve, a driving pin slideable in the sleeve, a hand grip affixed to an end of the pin extending from the sleeve, and means mounted within the sleeve to prevent withdrawal of the pin therefrom.

In one embodiment of the invention a removable foot is provided on an end of the sleeve opposite the hand grip. The foot has an enlarged flat face transverse to the longitudinal axis of the sleeve and covering the end edge of the sleeve. The foot is employed generally in connection with finish work to prevent marring of the wood. In a preferred form the foot has a second flat face which may be parallel to the longitudinal axis of the sleeve, i. e. perpendicular to the first mentioned face. Alternatively, the second flat face may be inclined with respect to the longitudinal axis of the sleeve. In this latter case, the second face and the first mentioned face may include either an acute or an obtuse angle.

A feature of the invention is the adjustability of the sleeve. In addition to permitting regulation of the depth of drive of a nail, brad or tack, this feature of adjustability is necessary in order to permit the use of the above described foot. Thus, to properly serve its function when used in finish work, the flat transverse face of the foot must enclose the end edges of the sleeve. The driving pin must therefore project beyond the end of the sleeve, to be flush with or project beyond the face of the foot. This is accomplished by shortening the sleeve an appropriate amount.

The foregoing and other features of the invention will be more clearly understood with reference to the following detailed description thereof taken in conjunction with the accompanying drawing in which:

Fig. 1 is an elevation view of the tube hammer as it might be applied in installing base shoe;

Fig. 2 is a sectional elevation of the tube hammer;

Fig. 3 is a detailed sectional elevation showing the functioning of the snubber spring in the sleeve;

Fig. 4 is a top view of one form of foot;

Fig. 5 is a side elevation of an alternative form of foot; and

2

Fig. 6 is a side elevation of a foot modified by the application of a rubber surface to the flat transverse face.

Referring to Figs. 1, 2 and 3 of the drawing, the tube hammer of the invention includes a sleeve 10, which comprises an elongated tube 11, telescoping into a shorter tube 12. The tube 11 is threaded at its upper end to screw into internal threading in the tube 12. A lock nut 14 holds tubes 11 and 12 in fixed relationship.

The upper end of the tube 12 is threaded to receive an enlarged collar 16.

A driving pin 18 is slideably mounted in the tube 12 and includes an elongated shank 19 and an enlarged head 20. As shown in Fig. 3, the shank 19 may be press fit into the head 20. Alternatively the shank may be threaded into the head or may be spot welded thereto.

The upper end of the shank 18 is provided with a weighted hand grip 22 which is shaped to fit snugly in the hand and which has annular lips 23 and 24 at the top and bottom respectively to prevent the user's hand from slipping off the grip.

A helical spring 26 is disposed within the upper end of the tube 12 around the shank 19. The spring 26 supports an annular washer 27 at its lower end through which the shank 19 is freely slideable. As shown in Fig. 3 when the shank 19 is raised in the sleeve 10, the shoulder 20A formed between the shank and the head 20 engages the washer 27. Further retraction of the driving pin compresses the spring 26. Retraction of the pin is snubbed by the spring. In this manner I have eliminated "jumping" which will occur if the shoulder 20A is allowed to impinge directly on the collar 16.

In a preferred embodiment of the invention the collar 16 is provided with an annular resilient washer 30 bonded to its upper face so as to reduce the shock consequent upon impingement of the hand grip against the collar.

Although not a necessary feature of the invention the head 20 of the driving pin is preferably magnetized so that the head of a nail, tack or the like may be held there again, prior hammering it into the wood. This is a common practice in conventional tube hammers.

As hereinbefore described the tube hammer includes a removable foot 32 which is generally frusto-conical or bell shaped. The foot is provided with a bore 33 of substantially the same diameter as the tube 20. The lower end of the bore 33 is restricted by an inwardly projecting annular lip 34 which reduces the size of the bore 55 to the inside diameter of the tube 11. The upper

edges of the foot are slotted at 35 and 36 so that the foot may be snapped on and off of the sleeve 10.

The foot has a flat bottom face 38 which lies in a plane transverse to the longitudinal axis of the sleeve 10 and which bears against the wood or other material in which the nail is to be driven. The relationship of the foot is illustrated in Fig. 1 wherein the tube hammer is shown in the position to drive a finishing nail into a base shoe 40 at the juncture of a wall 41 and a floor 42. The increased area of contact between the tube hammer and the material into which the nail is to be driven which is afforded by the flat face 38 of the foot substantially eliminates marring of the wood. In using the hammer for rough work the foot 32 may be removed from the end of the hammer if desired.

In the foot shown in Figs. 1, 2 and 4 a second flat face 44 is formed on a side of the foot in a plane parallel to the longitudinal axis of the tube 10, i. e. perpendicular to the plane of the base 38. This second flat face permits closer placement of a nail with respect to a vertical surface without appreciably reducing the beneficial effects of the foot. An alternative embodiment of the foot as shown in Fig. 5 includes a second flat face 46 inclined toward the longitudinal axis of the sleeve and including an obtuse angle with a first transverse flat face 47. This type of foot finds application in corner hammering as for example installation of base shoe. The inclined face 46 may be placed against the wall, as for example the wall 41, each time a nail is driven to insure that each nail will be driven at the same angle and at the same relative position in the base shoe. Alternatively, the second face may be inclined toward the longitudinal axis of the sleeve in the opposite direction so as to include an acute angle with the bottom face.

To further eliminate any marring of finished surfaces the foot 32 may be provided with an annular rubber gasket 48 bonded to the transverse flat face 38. (See Fig. 6.)

When the foot 32 is used, the distance between the upper face of the stop or collar 16 and the working surface is increased by the thickness of the annular lip 34. To permit flush driving of a nail the sleeve 10 is shortened by screwing the tube 11 further into the tube 12 to reduce the overall length by an amount equal to the thickness of the lip 34. To accomplish this adjustment the lock nut 14 is backed away from the tube 12, the tube 11 is threaded farther into the tube 12, and the lock nut is retightened to hold the tubes 11 and 12 in the new position. Similarly, when the foot as shown in Fig. 6 is em-

ployed, the tube must be shortened sufficiently to compensate for the thickness of the gasket 48 as well as the lip 34. Thus the foot would be in effect inoperative in the absence of provision for variable adjustability of the sleeve 10.

It is apparent from the foregoing description of the construction and operation of the tube hammer of the invention, that it possesses many features which differentiate it from the conventional tube hammer. Thus it is provided with (1) a variable stroke adjustment whereby the driving stroke may be varied throughout a range by adjustment of the tube length, (2) an internal snubber spring which reduces the impact of the driving pin on its up stroke, and (3) a finish foot which prevents marring and which is usable by reason of the adjustability of the driving stroke.

I claim:

20 A device for driving nails comprising an elongated sleeve adjustable with respect to its length including a first elongated tube threaded externally at one end, a second tube threaded internally at one end and externally at the opposite end, the first tube being threaded into one end of the second tube and adjustable therein, a lock nut threaded onto the first tube and adapted to fix the relative positions of the first and second tubes, and an enlarged collar threaded on the opposite end of the second tube, a driving pin slideable in the tubes through the collar, a hand grip affixed to an end of the pin extending from the tubes, and resilient stop means disposed within the larger of said two tubes and adapted to prevent withdrawal of the pin therefrom.
